UNITED STATES PATENT OFFICE.

HENRY M. MEETZE, OF CHARLOTTE, NORTH CAROLINA.

COTTON AND HAY PRESS.

SPECIFICATION forming part of Letters Patent No. 279,174, dated June 12, 1883.

Application filed January 13, 1883. (No model.)

To all whom it may concern:

Be it known that I, HENRY M. MEETZE, a citizen of the United States, residing at Charlotte, in the county of Mecklenburg and State 5 of North Carolina, have invented certain new and useful Improvements in Presses for Baling Cotton, Hay, and other Material, of which the following, when taken in connection with the accompanying drawings, forms a full, clear, 10 and exact description.

My invention relates to improvements in presses for compacting cotton, hay, straw, and like material into bales; and it consists in certain details of construction and arrangements 15 of parts, which will be fully described herein-after, and pointed out in the claims.

Referring to the drawings, Figure 1 is a side elevation of my press, showing the levers in position. Fig. 1^a is a view in perspective of 20 the frame, press-box, and pressure-plate, with the levers removed. Fig. 2 is a top view. Fig. 3 is a vertical longitudinal sectional view with the levers removed. Fig. 4 is a sectional end view on the line *x x* of Fig. 3. Fig. 5 is 25 a plan view of the pressure-plate. Fig. 6 is a detached view of one of the pressure-levers. Fig. 7 is a plan or top view of a detachable band, which may be used to hold the sides and 30 ends of the press-box together.

The object of my invention is to construct a press which shall be simple in all its parts, effective in its work, and so cheap that it can 35 come within the reach of every one.

Referring to the drawings, A A designate 35 the sills, of any desired or convenient length, to which the end pieces, B, of the press-box are rigidly attached by means of bolts, or in any convenient manner. To the end pieces of 40 the press-box are secured the bars or battens C, which are cut away near their ends to form a notch, *a*, for the reception of the bars or battens D, which hold the sides E of the press-box against the end pieces, B. The lower ends 45 of the side pieces, E, may be set in a recess in the sills, or they may be held in place by the lower battens or bars, D, the main object being to have ready access to the interior of the press-box after the bale has been pressed, to tie 50 the same and roll the bale from the press. This can be most readily done by making the sides of the press-box removable. Other

means may be resorted to to hold the sides of the press-box against the end pieces. A hinged band, as shown in Fig. 7, may be used to advantage, and when used it is made and applied in the following manner: 11 are metal bars or straps, hinged together at 22, and having their free ends provided with holes 3, to fit over staples 4, secured in the end pieces, B; and after the bale is placed in position the bent keys 5 are inserted in the staples to hold the metal bars thereon. For all practical purposes, however, and for economic reasons, I prefer to use the battens or bars of scantling or iron.

The end pieces, B, are provided with slots 65 or cut-away portions *b b* in their upper ends, for the reception of the projecting ends *c c* of the follower or pressure-board E. The pressure-board or follower F is constructed of any suitable size or kind of timber, and is adapted 70 to fit snugly within the cavity or walls of the press-box, and, as heretofore stated, the pressure-board is provided with projecting ends *c c*, which enter the slots or recesses in the end pieces, and project a short distance beyond 75 the same. The projecting ends *c c* of the pressure-board or follower should be made sufficiently strong to bear the force exerted by one or more of the pressure-levers, if so desired, and also serve as handles for moving the 80 pressure-board or follower to and from its position in the press-box; but where a screw-press is used in lieu of the levers for compacting the material in the press-box the projections *c c* need not be made so strong.

To the under side of the pressure-board or follower F are secured battens or cleats 6, at short intervals apart, so as to leave spaces 7, through which the wire, metal strap, or other tying material is passed in the process of tying 90 the bale. Similar battens or cleats, 8, are secured to the bottom board of the press in the same manner, so as to leave spaces 9 for the passage of the tie.

G G are the pressure-levers, two or more of 95 which are used at each end of the press. One end of said lever or levers is secured to a chain or rod, *d*, which is in turn secured to the sills A A by hooks, staples, or bolts, as may be desired. The free ends of the levers are passed 100 over the press-box from end to end, or from side to side, as may be desirable or convenient,

and rest on blocks H, of wood, which in turn rest on top of the pressure-board or follower, so that by pulling down on the free ends of the levers pressure is exerted on the pressure-board or follower to force it down onto the material to be pressed. The free ends of the levers may be provided with devices for securing weights thereto to assist in applying the requisite pressure to the material, as shown in Fig. 1. The levers G are notched, as shown at 10, Fig. 6, to engage with a tongue or projection, h, on the blocks H, so as to steady and retain the levers in their proper places.

The end pieces, B, are provided with swivel-hooks I, secured in the top thereof, to hold the levers down after the requisite pressure has been exerted on the bale, so that the side pieces, E, can be taken off and the pressure retained on the bale while the bands or ties are being put on the bale. Chains may be used for holding the levers down while the bale is being tied, instead of the swivel-hooks; but I prefer the swivel-hooks, for the reason that they are within easy reach of the operator, and are more convenient. In case the purchase of the levers is not sufficient to force the pressure-board or follower down to the bottom of the notches or slots in the end boards of the press, the follower may be retained in the position to which it has been forced by the levers by chains secured to it and to the sills, or by weights, so that the levers may be raised and another block of timber placed under the lever and on top of the previously-arranged block, so as to give the requisite purchase to the levers to force the follower down to the extent of its travel in the slots.

It is obvious that any number of levers may be used, some lying parallel with the length of the press, and others crossing it at right angles, while others may be made to impinge on the projecting ends of the pressure-board or follower.

By my construction of a press I obviate the necessity of making a high or double press-box, resorting instead to two, three, or more pressures to each bale by removing the follower and filling the press-box full of the material to be pressed.

The advantages of my press are obvious. Its simplicity of construction enables an ordinary mechanic to make the same from materials which are commonly on hand, or found on any well-regulated plantation. It is comparatively

inexpensive to build, and being light and so constructed as to be readily taken apart, it can be transported with ease from place to place.

The operation or method of using my press is as follows: The parts having been put together and firmly secured, the press-box is filled with the material to be pressed and well tamped down. The pressure-board or follower is now put on, the blocks arranged on top of the follower and the levers properly adjusted. Pressure is now applied by pulling down on the free ends of the levers and the pressure-board forced down to the bottom of the slots. The levers and follower are now removed and the press-box filled to the top, the levers and follower again adjusted, and pressure applied. This operation may be repeated as often as is necessary to form a bale of the required size. When a bale has been formed, the free ends of the levers are secured in their depressed position by means of the swivel hooks or chains, the sides of the press-box removed, and the bands or ties secured around the bale. The levers are now released and, together with the blocks and follower, removed from the press-box, when the compacted bale can be readily removed from the press-box.

Having thus described my invention, what I claim, and desire to secure by Letters Patent, is—

1. In a machine for pressing cotton, hay, &c., into bales, the end pieces, B, rigidly secured to the foundation-frame, and provided with the slots b, to receive the projecting ends of the follower, in combination with the sides E of the press-box, the whole of which are made removable, as set forth.

2. The combination of the stationary end pieces, B, provided with the slots b, with the follower F, provided with the projecting ends c, blocks H, lever G, chain d, and sills A, as set forth.

3. The combination of the end pieces, B, follower F, blocks H, chains d, and levers G with the swivel-hooks I, or their described equivalent, whereby the bale is held under pressure while the bands or ties are being put on the bale, as set forth.

HENRY M. MEETZE.
